[57] CLAIM

The ornamental design for a stackable medicine package, as substantially shown and described.

DESCRIPTION

FIG. 1 is a front elevation of a stackable medicine package showing my new design;

FIG. 2 is a left side elevation thereof, the right side elevation being a mirror image thereof;

FIG. 3 is a top plan view thereof;

FIG. 4 is a bottom plan view thereof;

FIG. 5 is a perspective view thereof;

FIG. 6 is a left side elevation thereof; and,

FIG. 7 is a rear elevation view thereof.

The stacked package shown in FIG. 6 in broken line is for ease of illustration only. The broken line showing a tablet in FIG. 5 is for illustrative purposes only and forms no part of the claim.

The texture depicted in portion on the lower surface of FIGS. 1 and 5 covers this entire surface.
